UNITED STATES PATENT OFFICE

CHARLES C. MERTZ, OF BALTIMORE, MARYLAND, ASSIGNOR OF ONE-HALF TO ALBERT W. GILL, OF BALTIMORE, MARYLAND

CONTROL FOR GUNFIRE

Application filed March 9, 1928. Serial No. 260,528.

This invention relates to an improvement in ordnance and is directed particularly to an improvement in automatic rapid fire arms.

One of the objects of the invention is the provision of means for regulating the rapidity of fire from a machine gun. Another object is the provision of an attachment for rapid fire guns that may be readily adjusted to change the speed of fire or to be entirely dispensed with as occasion may require.

With these and other objects in view, the invention resides in the novel arrangement and combination of parts hereinafter described and particularly pointed out in the appended claims, it being understood that minor changes may be made in the structure, within the scope of what is claimed, without departing from the spirit of the invention, or sacrificing any of the advantages thereof.

In the drawing:

Figure 1 is a view in side elevation of a portion of the breech of a machine gun, the present invention being attached thereto.

Figure 2 is a plan sectional view taken on the line 2—2 of Figure 1.

Figure 3 is a transverse sectional view the cutting plane being taken on line 3—3 of Figure 1.

Figure 4 is a detail perspective view of a bolt adapted for use with the present invention.

Figure 5 is a view similar to Figure 3 depicting a modified form of the device.

Figure 6 is a sectional view taken on the line 6—6 of Figure 5.

Figure 7 is a sectional view taken on the line 7—7 of Figure 5.

Figure 8 is a fragmentary sectional view of the cutting plane designated by line 8—8 of Figure 5.

In machine gun fire it has been found that due to vibration of the piece, the stream of bullets describe an ellipse on the target the longer axis of the ellipse being in a vertical plane. Machine gunners are therefore instructed to fire their weapon in "bursts" of a limited number of shots, about ten being the required number, and then to "bump" the gun. This instruction when properly carried out, produces a target having a series of

elliptically shaped line of bullet marks, the sides of each ellipse being spaced upon the other, so that the field is practically covered by gun fire.

In practical operation the regulation machine gun fires at such a rapid rate that the gunner invariably fires more shots than the requisite number, resulting in a waste of ammunition.

It is the function of the present invention to reduce the rapidity of fire and thus enable the gunner to more accurately do his work.

Referring to the drawings the numeral 1 designates the frame of a machine gun of well known make. The bolt 2 reciprocates within the frame in a well known manner.

Hingedly connected to the frame intermediate the ends thereof is a housing 3, the hinges being designated by the numeral 4. The housing supports a shaft 5, fixed against rotation by a pin 6 which also serves to secure the shaft to the housing.

A ball governor 7 is mounted for rotation on the shaft 5, the upper disk 8 thereof having a ratchet face 9. The lower disk 10 of the governor is mounted for rotation on a sleeve 11, the sleeve having a stop and brake collar 12 with which the disk 10 may engage. The sleeve 11 is threaded on the shaft 5 and is provided with a knurled finger-piece 13 for adjustment of the brake collar.

A collar 14 is secured to the shaft 5 by means of a pin 15 and supports the governor at its upper end.

Loosely mounted on shaft 5 is a gear wheel 16, the under side of which is provided with a ratchet face 17 for engagement with the ratchet face 9. A spring 18 surrounds the shaft 5 and is interposed between the top of the casing and the gear 16.

In attaching the device to the gun frame an opening 19 is made in the frame through which a portion of the gear 16 projects. The breech bolt 2 is also adapted for use of the device by forming a groove 20 in the block which provides clearance for the teeth of the gear projecting within the frame and a gear rack 21 formed on the block for engagement with the gear wheel.

A spring snap latch 22 retains the device in operative position.

In operation, as the bolt moves forwardly the teeth 21 engage the gear 16 and through the ratchet faces 9 and 17 transmit rotary motion to the governor, thus retarding the action of the bolt and thereby reducing the number of shots per minute from that of the unrestricted action.

10 In illustrating the modified form shown in Figures 5 to 8 inclusive parts corresponding to those of the preferred form have been designated by like numerals having a prime suffixed thereto.

15 In this form of the invention a centrifugal governor is dispensed with and a governor including an inclined plane is substituted. A sleeve 24 is formed as a part of the ratchet disk 8' and has a spiral groove 25 formed therein. A frame 26 comprising upper and lower heads 27 and 28 connected by bars 29 is mounted for longitudinal movement in the plane of the shaft 5'. The head 27 is provided with threads to engage the spiral 25.

20 25 A sleeve 30 is threaded exteriorly to engage a threaded opening in the case 3' and has a knurled head 31 at one end for rotating the sleeve and a collar 32 fixed thereto at the other end. Interposed between the collar 32 and

30 the head 28 is a compression spring 33.

25 The shaft 5' is fixed to the casing 3' as hereinbefore described. To prevent rotation of the frame 26 so that the parts 25 and 27 will be effective in compressing the spring 33, 35 a collar 34 is fixed to the shaft 5', the collar has arms 35 which extend through slots 36 formed in the bars 29. In this manner longitudinal movement of the frame 26 is produced to compress the spring 33, thereby to retard movement of the gear 16'.

40 It will be observed that through manipulation of the sleeve 30 to increase or diminish tension in the spring 33 that the bolt 2' will be retarded to a greater or less amount dependent on the tension in the spring.

45 It will also be noted that by releasing the latch 22 the attachment may be moved to an inoperative position and the gun may then be fired in the ordinary way.

50 What is claimed is:

1. In a firearm having a reciprocating bolt, a fly ball governor and means for connecting the governor and the bolt to retard reciprocation of the bolt.

55 2. In a device of the class described, the combination with a gun having a reciprocating bolt, of a fly ball governor, a gear for actuating the governor and a rack carried by the bolt for engagement with the gear to retard movement of the bolt.

60 3. In a device of the class described a housing, a shaft mounted in the housing, a governor rotatable on the shaft, a gear projecting from the housing and adapted to be rotated from outside the housing, a flexible connec-

tion between the gear and the governor to permit retroactive movement of the gear and means for regulating speed of rotation of the governor.

4. In a device of the class described, a gun including a fixed part, and a firing mechanism comprising a movable member, a governor, interengaging elements on the governor and on the movable member of the firing mechanism, said interengaging elements cooperating to connect the governor and the movable member of the firing mechanism, whereby the governor will retard the operation of the firing mechanism, a carrier for the governor, and means for holding the carrier on the fixed part of the gun, the last specified means being releasable to bring about a separation of the interengaging elements.

5. In a device of the class described, a gun having a firing bolt, a rack mounted directly on the firing bolt, a gear supported for rotation in the path of the rack on the firing bolt whereby the rack will mesh with the gear for a predetermined interval, and a fly ball governor connected to the gear and constituting means for exerting an uninterrupted retarding action on the gear and on the bolt during said interval.

In testimony whereof I affix my signature.

CHARLES C. MERTZ.
